UNITED STATES PATENT OFFICE.

THOMAS C. MCPHERSON, OF BEAVER FALLS, PENNSYLVANIA.

WOVEN-WIRE FABRIC.

Application filed February 12, 1925. Serial No. 8,808.

This invention relates to a woven wire fabric, suitable for use in door-mats, conveyer belting, metal lathing and for other purposes.

The invention has for its object the production of a fabric simple in its design and light in weight, but thoroughly braced, a fabric which has the same formation on both sides, so that it may be used either side up without any difference in results, and which is formed with transverse hinge lines about which it may be easily folded. When the fabric is laid flat, however, the portions of the connecting wires, forming the upper face, all lie in one plane, as do also the portions of the connecting wires forming the lower surface.

The specific construction of my improved fabric and its advantages will be more fully explained in connection with the accompanying drawing, forming a part of this specification.

In the drawing:

Fig. 1 is a plan view of a piece of fabric constructed according to my invention;

Fig. 2 is a side view taken on the line 2—2 of Fig. 1;

Fig. 3 is a fragmentary perspective view with one of the transverse wires removed, in order to better illustrate the formation of the loops;

Fig. 4 is a fragmentary perspective view of a slightly modified form of the invention; and

Fig. 5 is a sectional view taken on the line 5—5 of Fig. 4.

As illustrated in Figs. 1, 2 and 3, the fabric comprises a succession of transverse wires 10 forming hinge lines, and extending from side to side of the fabric, the end portions of these wires being bent substantially at right angles, as shown at 11, to form the edges of the fabric, and terminating in eyes 12, which form hinges about the next transverse wire. The intermediate portions of the wires 10 are connected by a series of wires which are looped about the transverse wires 10 to form a mesh work, the entire piece of fabric being hinged to fold freely about any one of the hinge lines formed by the wires 10. Each of these connecting wires begins at one side of the fabric with an end 13, which is looped about one of the transverse wires, and extends thence, as at 14, to the next transverse wire about which it forms a loop 15. The connecting portion

14 is thus beneath both of the transverse wires 10, and the loop 15 then passes upwardly about the second transverse wire, and thence obliquely alongside the same, as at 16, for a distance equal to the width of the mesh, then passes beneath the transverse wire, and forms a loop about the same, as at 17, passing thence, as at 18, to the first wire. The second connecting portion 18 is above both transverse wires, and is continued downwardly to form a loop 19 about the first transverse wire, and then continues obliquely upwardly alongside the latter as indicated at 20, forming another loop 21 about the same, from which the wire continues in the same manner as before, until it terminates in an eye 22 at the other side of the fabric.

By the construction described above, a fabric is formed which is thoroughly braced, yet light in weight, and which is freely flexible about any one of the transverse hinge wires 10. When the fabric is laid flat, all of the connecting portions 18 lie in a single plane and form the upper surface of the fabric, while all of the portions 14 lie in a single plane which forms the lower surface of the fabric. The upper and lower surfaces are exactly alike, so that the fabric may be reversed without any change in its function.

In the modified construction shown in Figs. 4 and 5, the transverse hinge wires 10 are arranged in the same manner, and the connecting wires are looped in the same manner, except that the connecting portions 23, which form the upper surface of the fabric, alternate with the connecting portions 24, which form the lower surface of the fabric; whereas, in the first construction described, the connecting portions 18, forming the upper surface of the fabric, are arranged to form substantially continuous longitudinal lines which alternate with similar longitudinal lines formed by the lower connecting portions 14.

While I have shown and described in considerable detail the manner of constructing the fabric, it is, of course, to be understood that these details are capable of considerable modification without any material departure from the salient features of the invention as expressed in the claims.

What is claimed is:

1. A wire fabric comprising successive transverse wires forming hinge lines across

the fabric, and a series of wires looped about the transverse wires to form a mesh work, each wire of said series having a portion running from one transverse wire to the 5 next above the same, each end of said portion continuing downwardly to form a hinge loop about the respective transverse wire and then continuing obliquely upwardly alongside the transverse wire, then 10 passing over the same to form another hinge loop and returning beneath the same to the under side of the other transverse wire and about the same to form another hinge loop.

2. A wire fabric comprising successive 15 transverse wires forming hinge lines across the fabric and connected by a series of wires looped about the same to form hinges, each of said series of wires passing from a loop on one transverse wire to the loop on the 20 next, above both of said transverse wires, then continuing alongside the second transverse wire to another loop, and returning from the last-mentioned loop to a loop on the first transverse wire, said return portion being beneath both of said transverse 25 wires.

3. A wire fabric comprising successive transverse wires, each of said wires having 30 end portions extending longitudinally of the fabric and forming hinge connections

about the succeeding wire, and a series of wires looped about said transverse wires to form hinges, each of said series of wires passing above two adjacent transverse wires and forming loops about both, then continuing 35 alongside the respective transverse wires for the width of the mesh, then forming another loop about the same, and returning thence to the other transverse wire, the return portion being beneath both trans- 40 verse wires.

4. A wire fabric comprising successive transverse wires, each of said wires having end portions extending longitudinally of the fabric and forming hinge connections 45 about the succeeding transverse wire, a series of wires connecting the transverse wires between the side edges of the fabric and looped about the transverse wires to form hinges, each of said series of connecting wires continuing from side to side of the fabric and successively passing from one transverse wire to the next, above both of 50 said transverse wires, and returning below said transverse wires.

In testimony that I claim the foregoing as my own, I have hereto affixed my signature.

THOMAS C. McPHERSON.
